UNITED STATES PATENT OFFICE.

ABNER D. BAKER, OF SWANTON, OHIO.

WATER-LEVEL CONTROL FOR BOILERS.

Application filed May 18, 1922. Serial No. 561,949.

This invention relates to means for use in connection with steam engines, for returning the water of condensation from the exhaust steam condenser to the associated boiler and maintaining an approximately constant normal level of water in the boiler.

An object of the invention is the provision in combination with a steam engine and its boiler, of simple and efficient means for continually returning the water of condensation from the exhaust steam of the engine to the boiler and which is automatically operable to introduce fresh water into the boiler as the water therein diminishes by reason by leakage, or from other causes, whereby the supply of water in the boiler is approximately maintained constant, thus enhancing the efficiency of this type of apparatus and rendering the use of steam engines in automobiles, trucks and tractors highly practicable and efficient. Further objects and advantages of the invention will be apparent from the following detailed description thereof.

While the invention in its broader aspect is capable of embodiment in numerous forms, a preferred embodiment thereof is illustrated in the accompanying drawings, in which,

Figure 1 is a side view of a steam tractor embodying the invention with parts broken away and removed, and Fig. 2 is an enlarged sectional detail of the double pump used in connection with the invention.

Referring to the drawings, 1 designates a tractor frame supported by wheels 2 and having a boiler 3 mounted on its rear end, and an engine 4 and exhaust steam condenser 5 mounted on its forward end. A pipe 6 connects the engine exhaust with the condenser.

The boiler 3, in the present instance, is of the water tube type and has a steam drum 7 at its top and is provided below its normal water line with a header 8, which has connection through pipes 9 with a series of headers 10 for the water tubes. The arrangement of the headers and tubes is immaterial so far as the present invention is concerned and may be changed to suit the particular boiler construction desired.

In carrying out the feature of my invention a pump casing 11 is secured to the frame 1 at a side of the engine and forms, in the present instance, two separate pump

cylinders 12 and 13 in which respective pistons 14 operate. These pistons are connected to a common rocker lever 15, which is in turn connected by a link 16 to an operating crank 17 of the engine. The pump cylinder 12 has its intake passage 18 in check-valve controlled communication with the bottom of the condenser 5 through a pipe 19. The outlet passage 20 of the cylinder 12 is in check-valve controlled communication through a pipe 21 with a pipe 22 in communication at one end with the header 8 through an outwardly opening check valve 23 and a normally open manually controlled valve 24 therein. The pipe 21 is provided with a check-valve 25. It is thus evident that operation of the pump piston 14 will effect a positive feeding of the water of condensation from the condenser 5, back to the boiler system, the water being introduced into such system in the present instance at the header 8.

The pump cylinder 13 has its inlet side in check-valve controlled communication through a pipe 26 with the bottom of a water storage tank 27, which is carried below the boiler in the tractor frame 1. The outlet side of the cylinder 13 is in check-valve controlled communication through a pipe 28 with a pipe 29, which leads down into the top of the tank 27, the communication between the pipes 28 and 29 being controlled by a thermostatic valve 30. The thermostat 31 of the valve is in communication with a portion of the boiler circulating system, in the present instance, with a pipe 32 which extends from the steam drum 7 to the header 8, the connection of the thermostat with said pipe being slightly below the normal level of the water in the boiler so that when the water in the boiler lowers slightly below normal steam will be admitted to the thermostat to effect an expansion thereof and a closing of the valve 30. Upon a closing of the valve 30 the water which is pumped from the tank 27 and forced up through the pipe 28 can no longer return to the tank through the by-pass pipe 29 and is required to take another course, which in the present instance is through a pipe 33 into the pipe 22 from whence it passes into the boiler through the header 8. The passage through the pipe 33 is normally closed by a check-valve 34, which opens under pressure of the pump 13, 14 when the valve 30 is closed. The

water continues to be pumped from the tank 27 in this manner into the boiler until the boiler water is returned to normal level, and shuts off the steam to the thermostat 5 31, thereby permitting a cooling of the thermostat and a consequent opening of the valve 30, after which the water which is pumped from the tank 27 is returned thereto through the pipe 29 until the water supply 10 has again lowered sufficiently to permit an operation of the thermostat to close the valve 30. 35 is a hand controlled valve to be used when valve 30 fails to work, and also for raising the water level in boiler before shutting engine down.

It is evident in the use of a boiler equipped with my invention that if the engine associated therewith is using 100 lbs. of steam or a much larger or smaller amount, the 20 water level in the boiler will remain the same because there is always the same amount of water returned to the boiler that the engine takes out except in case of leaks. If the water in the boiler falls below normal 25 by reason of leaks or from any other cause, the thermostatic valve 30 is closed causing the water which is pumped from the supply tank 27 and which would otherwise be returned thereto, to be forced into the boiler 30 through a check valve controlled line. So long as the water in the boiler is of the proper height, the thermostatic valve remains open so that the water pumped from the supply tank 27 is continually returned 35 thereto. An advantage of my invention is that the water returned to the boiler from the condenser is at a temperature of nearly 212° F., thereby obviating the necessity of using a reheater in connection with the exhaust. With my invention the undesirable 40 spasmodic system of water supply to the boiler heretofore used is avoided and a constant flow of water at all times to the boiler, to maintain the normal water level therein, 45 is insured.

I wish it understood that my invention is not limited to any specific construction, arrangement or form of the parts, as it is capable of embodiment in numerous forms 50 without departing from the spirit of the claims.

Having thus described my invention, what I claim as new and desire to secure by Letters Patent, is,

55 1. In combination, a steam boiler, means operated by steam from the boiler, a condenser for receiving the exhaust steam from the operating means, means operable to positively and directly return all water of condensation from the condenser to the boiler, a source of water supply, a line of communication extending from the source of supply and then back to the same and having a check valve controlled in communication 60 65 with the boiler, a thermostatic valve in said

line operable to close the same when the water level in the boiler falls below a predetermined point and thereby prevent the return of water through the line to the supply means, and means in said line for continually effecting a circulation of water from the source of supply and back to the same when the thermostatic valve is open and forcing the water through the check-valve controlled communication to the boiler when said valve is closed. 70 75

2. In combination, a steam boiler, means operated by steam from the boiler, a condenser for receiving the exhaust steam from the operating means, means operable to positively and directly return all water of condensation from the condenser to the boiler, a water supply tank, a pipe line leading from the tank and back to the same, a normally open valve in said line automatically 80 operable to close the line when the water level in the boiler falls below a predetermined point, said line having check-valve controlled communication with the boiler at a point intermediate the supply tank and automatic valve, and means continually operable to create a circulation of water from the supply tank through said line and back to the tank when the automatic valve is open and through the check-valve controlled communication to the boiler when the automatic valve is closed. 85 90 95

3. In combination with a steam generating means, means actuated by the steam therefrom, means for condensing the exhaust steam from the steam-actuated means, a make-up water supply, a pair of pumps having a single actuating means operable by the steam actuated means, one pump continuously returning the water of condensation from the condensing means as delivered thereto by the steam actuated means back to the steam generating means and the other pump supplying make-up water to the steam generating means, and means for permitting the said other pump to function when the water in the steam generating means falls below a predetermined level. 100 105 110

4. In combination with steam generating means and means actuated by the steam therefrom, a condenser to receive the exhaust steam from said steam-actuated means, means to convey the water of condensation from the condenser to the steam generating means, a source of water supply, means to convey water from the said source of water supply to the steam generating means, means connected to the last named conveying means to by-pass the water from the source of water supply back to the latter, means in the by-pass to shut off the passage of water therethrough, and means controlled by the level of the water in the steam generating means to operate said shutoff means thereby to cause the water from the source of supply 115 120 125 130

to enter the steam generating means when the level of the water in the latter falls below a predetermined level.

5. In combination with a steam generating means and means actuated by the steam therefrom, a condenser to receive the exhaust steam from said steam-actuated means, means to convey the water of condensation from the condenser to the steam generating means, a source of water supply, means to convey water from the said source of water supply to the steam generating means, means connected to the last named conveying means to by-pass the water from the source of water supply back to the latter, means in

the by-pass to shut off the passage of water therethrough, means controlled by the level of the water in the steam generating means to operate said shut off means thereby to cause the water from the source of supply to enter the steam generating means when the level of the water in the latter falls below a predetermined level, a pump associated with each of the water conveying means, and a single means to actuate each of the pumps in unison. 20

In testimony whereof I have hereunto subscribed my name to this specification.

ABNER D. BAKER.
